UNITED STATES PATENT OFFICE

2,606,225

TURRET TYPE SLIM LINE LAMP HOLDER

John M. Pistey, Fairfield, Conn., assignor to General Electric Company, a corporation of New York.

Application July 31, 1950; Serial No. 176,829

3 Claims. (Cl. 173—328)

1

This invention relates to lamp holders for lamps of the fluorescent or gas-filled type and particularly to an improved lamp holder and safety features for the mounting thereof.

In modern fluorescent lamps of the gas-filled type, it is common to have but a single terminal on each end of a lamp. This lamp is then put in a circuit with a ballast transformer, usually an autotransformer which supplies to the lamp a voltage higher than the line voltage. With this arrangement, the holder for one end of the lamp is called the high voltage lamp holder and the holder for the other end of the lamp is called the low voltage lamp holder. The latter is customarily provided with a pair of contacts in series with one side of the supply line, which contacts are interconnected only when a lamp terminal is inserted into that holder.

With installations of the subject type, it is common to position each of the lamp holders at a fixed distance apart. One end of the lamp is then first inserted into the high voltage lamp holder by pushing against a spring therein to permit the other end of the lamp to be inserted into position in the low voltage lamp holder.

The spring biased terminal is used for the high voltage end of the lamp holder to assure that contact is made, or that a complete circuit is made across the low voltage lamp holder.

In order to meet requirements of the Underwriters Laboratories, all connecting screws in the high voltage end of the lamp holder must be suitably insulated to be protected from any contact with grounding material of the lamp holder or of surfaces on which it may be mounted.

While lamp holders of the spring biased type have been used for the high voltage end, there is still need in the art for an improved lamp holder of the spring biased type that will provide positive contact between the lamp holder and one end of the lamp, and which will be rugged and economical to manufacture.

It is an object of this invention to provide a new and improved lamp holder for fluorescent lamps of the gas-filled type.

It is a further object of this invention to provide a new safety feature for the mounting of the high voltage end of a lamp holder which will assure the insulating of all connecting screws therein.

Further objects and advantages of this invention will become apparent and the invention will be more clearly understood from the following description referring to the accompanying drawing and the features of novelty which characterize this invention will be pointed out with

2

particularity in the claims annexed to and forming a part of this specification.

Briefly, this invention comprises an improved high voltage lamp holder which is provided with an insulating cylinder and movable contact piston for each lamp and an insulating safety feature which prevents the proper installation of the lamp holder until all connecting screws are protected and insulated.

In the drawing, Fig. 1 is a side view, partly in section, of a fluorescent lamp installation of the improved type; Fig. 2 is an end view, partly in section, of the lamp holder shown in Fig. 1 and taken through the line 2—2 in the direction of the arrows; Fig. 3 is a top view partly in section of the high voltage lamp holder shown in Fig. 2; while Fig. 4 is another view of the top of the lamp holder shown in Fig. 2 with the dotted line and solid line indicating two positions of the insulating strip in the lamp holder.

Referring to the drawing, a lamp installation 1 is shown comprising a lamp 2 installed in a high voltage holder 3 and a low voltage holder 4. The lamp 2 is provided with a pair of contacting prongs 5 and 6 shown in engagement respectively with a high voltage contact plate 7 and a low voltage contact plate 8.

The high voltage holder 4 comprises a casing 9 which encases one or more plastic cylindrical contact holders 10, contact pistons 11 for each of the contact holders, a spring 12, and a conducting bar 13 which is connected to a ballast transformer through terminal or set screw connections 14, shown more particularly in Fig. 4. A cover plate 15 is held by a set screw 16 in engagement with the casing 9 to position the contact holders 10.

Each of the contact holders 10 is a cylindrical section of some plastic material provided with a plurality of grooves 17 which extend almost the complete axial length of the contact holder 10, but which terminate short of the outermost portion to act as stops for sliding pintles 18, which are integrally cast with plastic contact pistons 11 and which engage the grooves 17. The spring 12 engages contact plate 7 which is formed in the plastic piston contact 11. Spring 12 is under compression between contact plate 7 and conducting bar 13 to insure good electrical contact between the conducting bar 13 and the contact 7 in piston contact 11. With this structure, piston contact 11 can be moved in opposition to the bias of the spring towards conducting bar 13 to provide for the insertion of lamp 2 in the lamp holder.

Casing 9 is provided with a plurality of in-

dents 19 which are engageable with a corresponding number of openings provided in brackets 21 secured to the cover plate 15. The combination of the indents 19 and the openings 20 with set screw 16 which is engageable with a threaded bore 23 secured in the casing 9 gives firm three point contact between the cover plate 15 and the casing 9. Cover plate 15 further defines a pair of openings 24 engageable with the contact holders 10, which, in turn, have a cut-away portion 25 to prevent the contact holders 10 from passing through the cover plate 15.

Conducting bar 13, as shown more particularly in Fig. 2, connects the center of spring 12 to an insulating block 26 which is positioned within the casing 9. The insulating block is of substantially the same length as the rear portion 27 of casing 9. Casing 9, in turn, is provided with a pair of indents 28 engageable with a corresponding pair of grooves 29 in the insulating block 26 to allow for the sliding of the insulating block 26 into or out of the casing 9. The insulating block 26 is held by set screw 16, which is in engagement with the threaded bore 23. The combination of the indents 28, the grooves 29, and set screw 16 position the insulating block 26 in spaced apart relationship from the rear side 30 of the casing 9 to allow for the sliding of an insulating strip 31 between the insulating block 26 and the rear side 30. Insulating strip 31 has, as an integral part thereof, a portion 32 extending transverse to the rear side 30 and parallel to the bottom 33 of the casing 9. Insulating block 26, in turn, has cast integrally therewith a spacer strip 34 which positions the insulating block 26 above the bottom 33 of the low voltage lamp holder 3. Consequently, portion 32 of insulating strip 31 is free to slide between insulating block 26 and the bottom 33 of casing 9.

Insulating block 26 is further provided with a stop 35 extending away from the insulating block a distance equal to that of spacer strip 34. Insulating strip 31 has formed in its bottom portion 32 an opening 36 engageable with spacer strip 34 and an opening 37 engageable with stop 35. This structure allows for the sliding of insulating strip 31 a fixed distance in one direction or another relative to the insulating block 26.

The conducting bars 13 are secured to insulating block 26 by rivets 38. A plurality of conducting strips 39 connect the rivets 38 to set screws 14, which, in turn, are the connecting screws for connecting the high voltage lamp holder to a ballast transformer (not shown).

Insulating strip 31 further defines a plurality of openings 40 which facilitate the positioning of a screwdriver or similar tool (not shown) in engagement with the set screws 14 to allow for the connecting of conductors to the set screws 14. Insulating strip 31 has as an integral part thereof a pair of extending ears 41 at each end which extend away from and in a plane with the insulating strip 31. The ears 41, when openings 36 and 37 of insulating strip 31 are moved into engagement with either side of the spacer strip 34 and stop 35, are adapted to cover one of a pair of keyhole slots 42 which are positioned in the rear side 30 of casing 9 to provide for the positioning of the high voltage lamp holder on a supporting structure of some kind.

The openings 40 and the ears 41 are so positioned in relation to the keyhole slots 42 and the stop 35 that one of the keyhole slots 42 is covered by one of the ears 41 if one of the set screws 14 is exposed. Specifically, in order to secure the

high voltage lamp holder 3 to any supporting structure by means of the keyhole slots 42, it is necessary that the insulating strip 31 be positioned between the keyhole slots 42. When this is done, the ears 41 expose the keyhole slots 42 and, at the same time, the insulating strip 31, because of the positioning of the openings 40, covers the set screws 14.

This is particularly shown in Fig. 3 where the set screws 14 are indicated by dotted lines as being behind the insulating strip 31 when the ears 41 are positioned between the keyhole slots 42. Fig. 4, on the other hand, indicates that the righthand ear 41 should be positioned to cover the corresponding keyhole slot 42 in order to expose one of the set screws 14 and that the strip 31 must then be positioned with the opposite ear 41 in engagement with the opposite keyhole slot 42 in order to expose the other set screw 41 for connection to a conductor leading to a ballast transformer. With this structure, the insulating strip 31 covers the set screws 14 in order to allow for high voltage holder 3 to be installed on some supporting structure by means of keyhole slots 42. Consequently, the Underwriters Laboratories, Inc. specifications are met with this simple and unique construction.

Modifications of this invention will occur to those skilled in the art and it is desired to be understood, therefore, that this invention is not to be limited to the particular embodiment disclosed, but that the appended claims are meant to cover all the modifications which are within the spirit and scope of this invention.

What I claim as new and desire to secure by Letters Patent of the United States is:

1. An improved lamp holder for a gas-filled lamp of the type having electrical contacting prongs on each end thereof comprising, a casing defining a cavity and a plurality of mounting holes, a cover plate cooperating with said casing to substantially enclose said cavity, a cylindrical insulating contact holder having a recessed outer edge, said cover plate defining an opening engageable with said recessed outer edge to position said insulating contact holder in said cavity, an insulating contact piston including an electrical contact axially slideable in said contact holder, stop means for limiting the movement of said contacting piston relative to said contact holder, a coil spring biasing said contact piston towards the outer edge of said contact holder, terminal screw means positioned in said casing to connect said lampholder in an electrical circuit, and electrical conducting means including said spring for connecting said contact piston to said terminal screw means.

2. An improved lamp holder for a gas-filled lamp of the type having electrical contacting prongs on each end thereof comprising, a casing defining a cavity and a plurality of mounting holes, a cover plate cooperating with said casing to substantially enclose said cavity, a cylindrical insulating contact holder having a recessed outer edge, said cover plate defining an opening engageable with said recessed outer edge to position said insulating contact holder in said cavity, an insulating contact piston including an electrical contact axially slideable in said contact holder, stop means for limiting the movement of said contacting piston relative to said contact holder, a coil spring biasing said contact piston towards the outer edge of said contact holder, terminal screw means positioned in said casing to connect said lampholder in an electrical circuit within said cavity, electrical conducting

means including said spring for connecting said contact piston to said terminal screw means, a slideable insulating strip to insulate said terminal screw means and defining an opening giving tool access to said terminal screw means, and a plurality of ears on said insulating strip slideable with said strip to cover one of said mounting holes when said terminal screw means is exposed and to expose all of said mounting holes when said connecting screw means is insulated by a solid portion of said insulating strip.

3. An improved lamp holder for a gas-filled lamp of the type having electrical contacting prongs on each end thereof comprising, a casing defining a cavity, a plurality of mounting holes, with spring biased electrical contacting means positioned within said case to be engageable with the prongs of a lamp, terminal screw means positioned in said casing to connect said lamp-holder in an electrical circuit, electrical conducting means connecting said terminal screw means with said contacting means, a slideable insulating strip including means for positioning the same on said casing for insulating said termi-

nal screw means, said strip defining openings giving tool access to said terminal screw means, a plurality of ears on said insulating strip slideable with said strip to cover one of said mounting holes when said terminal screw means is exposed and to expose all of said mounting holes when said connecting screw means is insulated by a solid portion of said insulating strip.
